A. N. GRIFFIN,
GATE AND POST CONSTRUCTION.
APPLICATION FILED JAN. 7, 1921.

Patented Feb. 21, 1922.

UNITED STATES PATENT OFFICE.

ALBERT N. GRIFFIN, OF DENTON, MARYLAND.

GATE AND POST CONSTRUCTION.

1,407,062.

Specification of Letters Patent. Patented Feb. 21, 1922.

Application filed January 7, 1921. Serial No. 435,681.

To all whom it may concern:

Be it known that I, ALBERT N. GRIFFIN, a citizen of the United States, and residing at Denton, in the county of Caroline and State 5 of Maryland, have invented certain new and useful Improvements in Gate and Post Constructions, of which the following is a specification.

This invention relates to improvements in 10 gate and post construction.

The primary object of the invention is to provide a gate especially adapted for farm use and special forms of posts employed therewith.

15 The invention contemplates a hinge post for mounting thereon for turning any form of gate desired, said post having extreme strength and formed of metal and concrete to render the same indestructible.

20 Among the other objects of the invention is the provision of a counter-balanced folding gate pivoted to the revoluble portion of the gate post. The said gate also is adapted to automatically fold upon being elevated to 25 its inoperative position.

The present post also is adaptable for 30 swingingly mounting any form of gate and adaptable for supporting old gates by the employment of the improvement attach- ments.

A still further object is to provide a post 35 structure for mounting a gate for swinging in such a manner that the gate is easily removed for storing during certain months of the year if desired while taking up a minimum amount of space by reason of its fold- able property.

With these general objects in view and others that will appear as the nature of the 40 invention is better understood, the same consists in the novel combination and arrangement of parts hereinafter fully described, illustrated in the accompanying drawings, and pointed out in the appended claims.

45 In the drawings forming a part of this application and in which like numerals refer to corresponding parts throughout the several views:

Figure 1 is an elevation partly in section 50 of the device showing the gate closed.

Figure 2 is a similar view with a gate illustrated in the elevated open position.

Figure 3 is a vertical sectional view of the hinge post, and

55 Figure 4 is a perspective view of the latch post.

Referring more in detail to the drawing, the hinge post upon which operation rests the successful working of the entire invention, consists of a concrete base 10 tapering 60 upwardly and securely embedded in the earth having rigidly-mounted therein the vertical rod 11 which however, may be tubular if desired, while a stationary joining collar 12 is mounted upon the top of the base. A supporting tube 13 is journalled for turning upon the rod 11 and extends slightly above the upper end of the rod having through such extended portion alining slots 14 while the angular bracket 15 is transversely pivoted through said post and slots by means of the pivot pin 16.

An ornamental cap 18 is mounted upon the open top of the tube 13 which prevents moisture from entering the tube.

Upon the outer end 19 of the bracket member 15 which normally lies in a plane above the opposite end 20 of the bracket, there is adapted to be mounted a suitable counter-weight and herein shown as a hollow container 21 with a removable cap and adapted to enclose the desired amount of weighing material 23. From this brief description of the hinge post, it will be evident that any form of gate secured to the lower end 20 of 80 the pivoted bracket will have its weight partially compensated by the counter-weight 21 while the same will have a free turning movement by reason of the journalled tube 13 which forms a part of the post. The fold- able gate employed with my hinge post comprises the upper tubular member 24 pivoted in parallel relation to a lower corresponding member 25 by means of the normally parallel slats 26 while a connecting strap 27 is centrally pivoted to said slats. A latch post 28 formed of a tubular member is rigidly mounted in the earth by means of the concrete base 29 similar to that of the hinge post while upon the top thereof is provided 90 the flaring head 30 having a central notch or depression 31 adapted to seat the extension 32 of the top member 24 which is readily locked therein by the pivoted latch 33. For convenience in manipulating the gate, the 100 extension 32 is provided with an upward terminal bend 34 having a knob 35 thereon while a socket 36 of semi-tubular form is secured to the latch post adjacent the bottom thereof and in which one end of the lower 110 member 25 is adapted to rest when the gate is closed.

The said gate as will be noted, is in the form of parallel members shiftable by reason of their pivotal connections to bring said members different distances apart while 5 uniformly maintaining their parallelism.

In the normal closed position of the gate as shown in Figure 1, the extension of the top member rests within the head of the latch post while the adjacent end of the 10 lower member is seated within the socket 36 and the latch 33 engaging the top member, the gate is locked closed.

By longitudinally swinging the lower member 25 to one side of the latch post, the 15 same unseats from the socket 36 and the transverse pin 40 through said lower member comes in alinement with the opening 41 positioned near the bottom of the latch post and provides for the entrance of said pin 20 in said opening to secure the gate locked in a partially open position. It will be seen that the position of the top member 24 is not altered but remains locked by the latch 33. Such provision while retaining 25 the gate closed against the larger animals, allows the smaller stock to pass through the partially opened portion.

For opening the gate, the latch 33 is released and the upper member 24 elevated 30 to the position shown in Figure 2 which manual movement is assisted by the counter-weight 21, the latter also retaining the gate in this position, while the weight of the lower member 25 causes the same to fold 35 together after the manner illustrated in Figure 2, it being evident that at any time of dis-engagement with the latch post that the gate by means of the tube 13 may be freely turned upon the hinge post and that while

remaining elevated, the action of the wind 40 thereon will only be to turn the same partially around.

While the form of the invention herein shown and described is what is believed to be the preferable embodiment thereof, it is 45 nevertheless to be understood that minor changes may be made in form, proportion and details of construction without departing from the spirit and scope of the invention as set forth in the appended claims. 50

Having thus described my invention, what I claim as new is:—

1. In a device of the class described a tubular post member having alined slots through the upper end thereof, an angular 55 bracket pivoted within said post, its opposite ends projecting through said slots, a counter weight upon one end of said bracket, and a gate rigidly secured to the other end of said bracket. 60

2. In a device of the class described, a tubular post member having alined slots in its upper end thereof, an angular bracket pivoted within said post and comprising a vertical central portion having oppositely 65 extending ends at right angles to the vertical portion and on a horizontal axis, the opposite ends of the bracket projecting through the slots within the post, a counter weight upon the upper end of said bracket, 70 and a gate rigidly secured to the lower end of said bracket.

In testimony whereof I affix my signature in presence of two witnesses.

ALBERT N. GRIFFIN.

Witnesses:

GERTRUDE CROSSAN DEEN,
K. A. MURCHISON.
